UNITED STATES PATENT OFFICE.

HARVEY L. FISHER, OF CHICAGO, ILLINOIS, ASSIGNOR, BY DIRECT AND MESNE ASSIGNMENTS, TO FISHER MANUFACTURING COMPANY, OF CHICAGO, ILLINOIS, A CORPORATION OF ILLINOIS.

TABULATOR FOR TYPE-WRITING MACHINES.

No. 874,059.

Specification of Letters Patent.

Patented Dec. 17, 1907.

Application filed April 22, 1901. Serial No. 56,923.

To all whom it may concern:

Be it known that I, HARVEY L. FISHER, a citizen of the United States of America, residing at Chicago, in the county of Cook, in the State of Illinois, have invented a certain new and useful Improvement in Tabulators for Type-Writing Machines, of which the following is a description, reference being had to the accompanying drawings, forming part of this specification:

My invention relates to attachments for typewriting machines commonly known as tabulators, whose purpose is to facilitate the listing of numbers, amounts, or other data, in proper order in vertical columns upon a sheet of paper, and it has for its object certain improvements upon the devices of this general character now in use or heretofore proposed, which will be hereinafter pointed out and fully set forth in my claims.

In the accompanying drawings, Figure 1 represents a top plan view of so much of a typewriting machine as is necessary to illustrate my present invention; Fig. 2 a rear elevation thereof; Fig. 3 a middle vertical section; Fig. 4 a detail from Figs. 2 and 3; and Figs. 5 to 12 details of the stop mechanism.

The same letters of reference are used to indicate identical parts in the several views.

I have illustrated my invention in the present instance as adapted and applied to the typewriting machine shown and described in my pending application, Serial No. 693,442, filed October 13, 1898, and it will be described with reference to such machine, although in its main features it is applicable to a wide variety of typewriters.

The construction and operation of the machine illustrated in the drawings, excepting my present improvement, are fully described in my aforesaid pending application, and may be here briefly referred to. The regular key levers A of the machine are fulcrumed at their rear ends, at B, and are connected to and operate type-bars (not shown) adapted to strike upon the upper forward side of the platen roller E mounted in the paper-carriage F which is supported at its forward side by a roller G resting and traveling upon a transverse rod H secured at its opposite ends to the frame work, and which carries at its rear side a rod I resting and traveling upon grooved supporting rollers J, Fig. 2.

Secured to the under side of the paper-car-

riage at its rear edge is a rack bar L, Figs. 1 and 3, which meshes with a pinion M fast upon a vertical shaft or spindle N mounted in a suitable bearing upon the frame work and having secured to its lower end an escapement wheel O provided with vertically depending teeth, Fig. 3. The paper-carriage is pulled to the left by a connection with a spring confined within a rotary barrel or casting P, as usual, and as it moves toward the left under the operations of the keys and space-bar W the pinion M and the wheel O are turned in one direction, and when it is restored to right hand position, preparatory to beginning a new line, they will turn in the opposite direction.

The escapement mechanism of the machine may be the same as that employed in the machine of my aforesaid pending application, and as it is there illustrated and described in detail it will suffice, for an understanding of my present invention, to explain here that the escapement dog which co-operates with the toothed escapement wheel O is actuated by an arm S, Fig. 3, fast upon a rock shaft T which has fastened to it at opposite sides of the machine forwardly projecting side arms U which carry at their front ends the universal bar V underlying the key-levers A, so that when any one of said levers is depressed the shaft T will be rocked to operate the escapement mechanism and advance the paper-carriage one step, a coiled spring S' serving to return the escapement dog to normal position when the operated key lever is released.

The foregoing is the normal operation of the escapement mechanism, under which the paper-carriage is advanced one letter-space at each operation of only one of the levers A; but, as explained in my aforesaid application, if the escapement dog be given an extreme or abnormal forward movement it will be entirely disengaged from the escapement wheel O, and thereby entirely release the paper-carriage from the control of the escapement mechanism and leave it free to be drawn to the left by its spring until arrested by the stop devices hereinafter described. In the present instance the means provided for giving the escapement dog such extreme forward movement consists of the tabulator key-levers A" forming part of my novel tabulating attachment, which key-levers are

fulcrumed at their rear ends at B'', Figs. 2 and 3, and at their forward ends have connected to them the lower ends of vertical rods or stems C'' carrying at their upper 5 ends the finger-buttons B'' indicating the denominational value of each lever. Each of the levers A'' is provided with an upwardly extending hooked arm E'' adapted to engage a cross-rod F'' connecting the side 10 arms U of the universal bar V which operates the escapement mechanism as heretofore described, and the adjustment of the parts is such that whenever any one of the tabulator levers A'' is depressed to its limit 15 of movement its hooked arm E'' will swing the frame U U V downward a considerable distance further than it is depressed by the normal operations of the regular type-levers A, with the result that the upper end of the 20 arm S will be thrown forward beyond its normal limit of movement and the escapement dog be thereby entirely disengaged from the escapement wheel O, so that the paper-carriage will be wholly released and left free to 25 be drawn to the left by its spring as before explained. For the purpose of preventing the paper-carriage being drawn too suddenly and violently toward the left, however, I provide a brake device operated by 30 the tabulator key-levers A'' and consisting of a friction spring G', Fig. 3, fastened at its lower end to the rockshaft T and adapted to bear at its upper end against the rear side of the rotary spring barrel or casing P. When 35 the shaft T is rocked forward by the operation of any one of the key-levers A'' the upper end of the spring G' will be forced against the rear face of the spring barrel and prevent too rapid rotation of it under the action of 40 the spring. This brake spring may be applied to the escapement wheel O, instead of the casing P.

Secured to the upper rear side of the paper-carriage near its middle, and projecting rearwardly therefrom, is a bracket plate H' which carries a graduated contact piece I', Figs. 1, 2 and 3, adapted to coöperate with stops J' mounted upon and adjustable longitudinally of a rock shaft K' which is mounted 50 at its opposite ends in bearings upon supporting brackets L' upon the frame of the machine, Figs. 1, 2 and 3, and surrounded at its right-hand end with a coiled spring K'' which serves to yieldingly hold it in and 55 turn it to normal position. The graduated contact piece I' is curved in cross section approximately concentric to the rock shaft K', Fig. 3, and provided upon its left hand side 60 with a series of stops or shoulders a arranged in regular retreating order from left to right and from front to rear, Fig. 1, and forming a series of contact surfaces separated from each other by the length of a regular letter space movement of the paper-carriage. These stops or shoulders a correspond in

number to the tabulator key-levers A'' and are adapted to coöperate with the stops J' upon the rock shaft K'. When said shaft is in normal position the stops J' stand out of the path of movement of the contact piece I' 70 upon the paper-carriage, so that the latter is free to be moved in either direction without regard to said stops. When, however, the shaft K' is turned rearward a greater or less distance its stops J' will be carried into line 75 with one or another of the shoulders a upon the contact piece I', so that if the paper-carriage be then permitted to move toward the left it will be arrested by the contact of the piece I' with the first stop J' standing in its 80 path. Now, by the means hereinafter described, the several tabulator key-levers A'' are arranged to coöperate with the rock shaft K' in such manner as to turn the latter 85 different degrees of distance according to the different denominational values of such key-levers, with the result that when any given key-lever is operated the shaft will be turned to a point to bring the stops J' into line with the corresponding shoulder or contact surface 90 a upon the contact piece I'. If the rock shaft K' be turned just far enough to carry the stops J' into line with the right hand and rearmost shoulder or contact surface a the paper-carriage will be permitted a maximum 95 movement to the left before being arrested by the first stop standing in the path of said contact piece I'; while if the shaft is turned so as to carry the stop J' into the path of some one of the shoulders a at the left of the one mentioned, the paper-carriage will be arrested at an earlier point in its movement 100 towards the left. There are in the present instance, as shown in Fig. 1, eight tabulator keys, which may be taken to represent, respectively, a decimal point or period and different denominations of value from units to millions, reading in regular order from right to left; and the graduated contact piece I' is provided with eight shoulders or contact surfaces a corresponding in relative position or order with the eight tabulator keys.

As will be seen from the foregoing explanation, whenever any one of the tabulator keys is operated the rock shaft K' will be so turned as to carry the stops J' into line with the corresponding shoulder or contact surface a upon the graduated contact piece I' carried by the paper-carriage, and inasmuch as the operation of such tabulator key will 110 also serve (in the manner and by the means heretofore explained) to disengage the escapement mechanism and release the paper-carriage, the result will be that the latter will be drawn to the left by its spring until 125 arrested by contact of one of the stops J' with the shoulder or contact surface a into line with which the stops J' have been carried, which shoulder or contact surface will be the one corresponding to the particular 130

tabulator key which had been operated, and the paper-carriage will consequently be arrested at a point for the printing to be effected in the denominational column of figures 5 corresponding to the tabulator key which has been operated.

Any suitable connections between the tabulator key-levers A'' and the rock shaft K' which will cause the operations of the different keys to turn the shaft different degrees proportionate to the denominational values or positions of the keys, may be employed for the purpose. In the present instance I employ a rock shaft M' journaled at its opposite ends in bearings upon the frame work of the machine, Figs. 2 and 3, and provided upon its under side with a depending plate or wing N' whose lower edge is inclined upwardly from the right toward the left of the machine (from left to right in Fig. 2), which wing is adapted to coöperate with a series of graduated cams O' formed upon the upwardly extended rear ends b of the tabulator key-levers A''. Owing to the different lengths of the vertical extensions b of the key-levers A'' and to the engagement of their cams O' with the wing N' at different distances from the axis of the rock shaft M', it follows that the operations of the different 30 key-levers will impart different degrees of movement to said shaft, and the construction and adjustment of the parts are such that the movement thus given the shaft by the operation of each tabulator key will correspond to the denominational value or position of such key. The shaft has secured upon its right hand end a vertically extending arm P' whose upper end is connected by a pivoted link Q' with an arm R' fast upon 40 and projecting forwardly from the rock shaft K', Figs. 3 and 4. When the shaft M' is rocked by the operation of any tabulator key the upper end of the arm P' carried by said shaft will be swung rearward, and, 45 through the medium of the link Q' and arm R', will turn the shaft K' rearward and swing the stops J' into line with the shoulder or contact surface a on the contact piece I' which corresponds to the operated tabulator 50 key, with the result that the paper-carriage, as it moves toward the left, will be arrested in position for the printing to be effected in the corresponding denominational column.

The cams O' are so shaped that after they 55 have swung the wing N' forward the proper distance they will pass under its lower edge but still remain in engagement with it and prevent its return in advance of the key-lever. In this manner the tabulator key-levers are 60 caused to impart the necessary movement to the parts to properly set the stops J' at the beginning of their own movement and to then hold said stops in such adjusted position while their continued movement 65 serves to depress the universal bar V far

enough to release the paper-carriage and apply the brake spring to the spring casing P, as before explained. The stops J' are thus set or adjusted before the paper-carriage is released and permitted to move, and 70 are maintained in adjusted position until the carriage is released and completes its movement and is arrested by one of the stops, whereupon, on the release of the operated tabulator key, the rock shaft K' will be returned to normal position by the action of the spring K'' applied to its right hand end, Fig. 1, and the stops J' be carried back out of the path of travel of the contact piece I' upon the paper-carriage. 80

Instead of employing a series of tabulator keys and connections for setting the stops J', other means for turning the rock shaft K' may be substituted and many of the advantages of my invention retained. Likewise, 85 even where the tabulator keys are employed for adjusting the stops they need not necessarily perform also the function of releasing the paper-carriage, since independent means may be employed for that purpose without 90 departing from the broader scope of my invention.

As will be understood from the foregoing the turning of the rock-shaft K' under the operations of the different tabulator keys 95 serves to determine the denominational position of the stops J', while the adjustment of said stops longitudinally of the rock shaft determines their columnar position. The stops J' may be of any suitable form to co-operate with the graduated contact piece I', and may be adjusted longitudinally of the rock shaft K' and secured in adjusted position by any suitable means. Thus, each stop may consist of a simple sleeve mounted 100 to slide lengthwise upon the shaft and provided with a set screw for fastening it thereto in adjusted position, and with a projecting lug to coöperate with the contact piece I'. In the present instance, however, the 110 stops which I have illustrated embody features of novelty both in respect to the method of adjusting them longitudinally upon the rock shaft and securing them in adjusted position thereon, and in respect to 115 their coöperation with the paper-carriage, which features will now be explained.

The provision for adjusting the stops and securing them in adjusted position may be 120 explained and illustrated independently of their other features of novelty, as by reference to Figs. 2, 5, 6, 7, and 8, where it will be seen that the rock shaft K' upon which the stops are mounted is provided upon its rear side with a longitudinal groove a', whose 125 lower wall is formed into or has secured to it a rack b'. Each of the sleeves A' which carry the stops has a screw c' passed radially through it and projecting at its inner end into the groove a' in the rock shaft, Figs. 6 130

and 7. By turning the sleeve in one direction upon the rock shaft the projecting inner end of the screw c' may be engaged with the rack b' , Fig. 6, and thereby lock the sleeve 5 from longitudinal movement on the shaft, while by turning the sleeve in the opposite direction the projection will be disengaged from the rack and carried into the free portion of the groove, Fig. 7, to permit the sleeve 10 to be adjusted longitudinally of the shaft. The sleeve has formed upon one end an enlargement or integral collar a'' , Fig. 8, having a milled surface to form a thumb piece for turning and adjusting the sleeve upon the 15 shaft. A spring is interposed between the sleeve and shaft and operates to yieldingly hold the sleeve in a position for the inner end of the screw c' to be engaged with the rack b' , Fig. 6, and the sleeve thereby locked from 20 movement longitudinally of the shaft. When it is desired to adjust the sleeve longitudinally of the shaft it is turned, against the resistance of such spring, until the projecting end of the screw is carried into the free portion of the 25 groove a' , Fig. 7, and after the sleeve has been then adjusted along the shaft and released the spring will turn it back to normal position upon the shaft and reengage the projecting end of the screw with the rack. In 30 the present instance this spring is a curved wire spring d' , Fig. 5, secured at one end to the face of a disk B' secured to or formed integral with the end of the sleeve opposite the milled thumb piece, and the opposite end of 35 the spring is bent inwardly and projects through a slot in the sleeve into engagement with the groove in the shaft.

When the sleeve is turned upward and forward, in the direction of the arrow, from the 40 position of Fig. 6 to that of Fig. 7, to disengage the inner end of the screw c' from the rack b' , this spring d' is put under increased tension, and serves to turn the sleeve backward to normal position, Fig. 6, whenever 45 the sleeve is released. The spring may be interposed between the sleeve and shaft in any other suitable manner, and such sleeve, so mounted upon and coöperating with a shaft provided with a longitudinal groove and 50 rack, may be employed for other purposes than carrying stops to coöperate with the graduated contact piece on the paper-carriage.

So far as concerns the operation of the tabulating device which has been thus far explained the stops J' which coöperate with the graduated contact piece I' may consist of simple lugs or projections on the sleeves A' , but for a purpose hereafter explained I prefer to employ a novel form of stop carried by and movable upon the adjustable sleeve, which may be now explained by reference to Figs. 8 to 11: As shown in Figs. 8 and 10, the disk B' upon the sleeve A' has pivotally hung to it a stop plate or disk C' which is provided upon its rear side with a projecting lug J' con-

stituting the stop which coöperates with the contact piece I' on the paper-carriage, and upon its forward side with another projecting lug e' for a purpose hereafter explained. The stop plate C' is pivotally hung to the 70 disk B' at the upper rear side of the latter, at x , and is provided with an elongated opening f through which passes the rock shaft K' and which permits a rocking or swinging movement of the plate C' upon the disk B' . In 75 normal position, Fig. 2, the stop lug J' upon the rear side of the plate C' projects rearwardly beyond the periphery of the disk B' , while when it is swung forward to the position shown in Fig. 10 it is carried within the 80 plane of the periphery of the disk. The disks B' are of such size as to permit the curved contact piece I' upon the paper-carriage to pass freely beneath but in close proximity to them, Figs. 8 and 10, so that they do not interfere with the movement of the paper-carriage. Likewise, when the stop plates C' are in the position shown in Fig. 10, with the lugs J' , within the periphery of the disks B' , they also will be out of the path of movement of the graduated contact piece I' . When, however, the plates C' are in the position shown in Fig. 2, with their lugs J' projecting beyond the peripheries of the disks B' , said lugs will project into the path of 90 travel of the contact piece I' whenever the rock shaft K' is turned rearward and the lugs J' thereby carried downward toward the under side of the shaft, Fig. 8. It results from this construction and arrangement of the parts 95 that with the stop plates C' in normal position upon their supporting disks B' , the rearward movement of the rock shaft K' consequent upon the depression of any tabulator key will swing all of the lugs J' downward into the path of travel of the graduated contact piece I' on the paper-carriage. The particular shoulder a of the contact piece I' with which the stop lugs J' will be brought into line by such turning of the rock shaft K' will 100 depend upon the degree of movement given the rock shaft, and consequently upon the particular tabulator key which may be operated to turn the shaft, and the adjustment of the parts is such as heretofore explained, that the stop lugs will be carried into line with that particular shoulder upon the contact piece which corresponds to the particular tabulator key operated. The paper-carriage will therefore advance until such shoulder of the contact piece I' comes in contact with the first stop lug J' in its path, whereupon the carriage will be arrested. Upon 105 now releasing the depressed tabulator key the spring K'' wound around the rock shaft 110 K' will return the latter to normal position, and disengage the stop lug J' from the shoulder of the contact piece I' which had come in contact with it at the movement of the paper-carriage. In disengaging itself from 115

such shoulder, however, the stop lug will be retarded by the friction between itself and the shoulder upon the contact piece with which it has been engaged, with the result 5 that the stop plate C' carrying such lug will be swung upon its pivot on the disk B' from the position shown in Fig. 8 to that shown in Fig. 10 and the lug J' be thereby carried within the periphery of the disk B'. To 10 facilitate and insure this operation of the parts the side of the lug J' facing the contact piece I' is beveled as shown in Fig. 9 and the coöperating faces of the shoulders a upon the contact piece are correspondingly 15 beveled, so that after a given shoulder has come in contact with one of the stop lugs and arrested the paper-carriage, and is being pressed against the lug by the force of the spring tending to move the paper-carriage 20 still further toward the left, as in Fig. 9, the beveled surface upon the lug will fit against the beveled surface upon the shoulder and materially increase the friction necessary to be overcome in moving the lug upward and 25 disengaging it from the shoulder at the return movement of the rock shaft, consequent upon the release of the tabulator key.

A curved wire spring g' confined in a recess provided for it between the disk B' and the 30 plate C', Fig. 10, and connected at one end to said disk and at its opposite end to said plate exerts a pressure upon said plate tending to swing it from the position shown in Figs. 3 and 8 to its opposite position shown in Fig. 35 10, the plate C' being normally restrained from such movement and yieldingly held in the position of Figs. 2 and 8 by a spring plunger h' confined in a bore in the disk B' and pressed by a coiled spring i' into engagement 40 with a recess j' in the surface of the plate C', Fig. 12. When the plate C' has been swung far enough from the positions of Figs. 3, 8 and 12 toward the position of Fig. 10 to disengage its recess j' from the end of the spring 45 plunger h' the spring g' will carry the plate C' onward to the position of Fig. 10 and engage its recess k' with the plunger h' as in Fig. 11, which latter will then serve to yieldingly hold the plate in the position of Fig. 10 until it is 50 swung back to the position of Figs. 2, 8 and 12, and its recess j' reengaged with the plunger h' to yieldingly hold it in that position, as hereafter explained.

The purpose of the movable stop plates C' 55 carrying the stop lugs J', as distinguished from a stop lug projecting rigidly from the disk B' or sleeve A', is to cause the stop lug to be carried entirely out of the path of the graduated contact piece on the paper-carriage after such contact piece has engaged and been arrested by the stop, so that the 60 same stop cannot be again thrown into the path of the contact piece by the next operation of a tabulator key. If a rigid stop, such 65 as a lug projecting directly from the sleeve

upon the rock shaft, be employed, it is necessary, after the arrest of the paper-carriage by any particular stop, that the contact piece shall move entirely beyond such stop before another tabulator key is operated, and if the 70 operations of the type keys necessary to print the desired amount in the column being tabulated do not suffice to thus advance the paper-carriage beyond the stop it must be spaced the necessary additional distance by 75 operation of the space bar or otherwise, since if a second tabulator key be operated before the contact piece I' on the paper-carriage has passed entirely beyond the stop with which it was last engaged such stop is liable to be 80 thrown into contact with the contact piece again at the operation of the next tabulator key, and the paper-carriage be thereby prevented from advancing to the next succeeding stop. By providing the movable stops 85 described, which are thrown out of operative position immediately after the arrest of the paper-carriage by them, it is not necessary to pay any attention to the movement of the paper-carriage prior to operating another 90 tabulator key, since by operating several tabulator keys immediately in succession the paper-carriage will be properly advanced to and arrested by the several stops in succession, so that in listing numbers in several parallel columns it is simply necessary, with the paper-carriage in right hand position, to press the proper tabulator key for the entry 95 of the desired amount in the first column, then operate the proper type keys to print 100 such amount in said column, then press the proper tabulator key for the entry of the desired amount in the next column, and then operate the proper type keys to print such amount in such column; and so on, with all 105 the parallel columns on the sheet of paper.

For the purpose of resetting all the stop plates C' at each return movement of the paper-carriage to right hand position, and thereby throwing all of the stop lugs J' outward beyond the peripheries of the disks B', into position to be swung into the path of travel of the graduated contact piece on the paper-carriage at the next operation of a tabulator key, there is provided a wiper arm D' 110 upon the paper-carriage, in this instance secured to the forward side of the graduated contact piece I', which wiper arm D' at the return movement of the paper-carriage to right hand position wipes over the lugs e' projecting from the forward sides of the stop plates C' and heretofore referred to, and swings all of said stop plates, upon their pivotal supports upon the disks B', from the position of Fig. 10 back to normal position, 115 Fig. 2, so that when a tabulator key is then depressed and the shaft K' thereby rocked all of the stop lugs J' will be swung downward into the path of travel of the graduated contact piece I' upon the paper-carriage, 120 125 130

ready to arrest the paper-carriage at successive stops upon the successive operations of the tabulator keys, as heretofore explained.

In another application filed by me on June 5 23, 1899, and bearing Serial No. 721,551, I have described and claimed an invention which is generic to the more specifically claimed invention of the present application.

Having thus fully described my invention, 10 I claim:

1. In a tabulating attachment for type-writing machines, the combination, with the transversely movable paper carriage, of a rock shaft, a plurality of stops mounted thereon and adapted to coöperate successively with the paper carriage to arrest the latter in different columnar positions, and a plurality of tabulator keys and connections for turning the rock shaft to adjust the stops 15 to arrest the paper-carriage at the desired denominational positions in the different columns, substantially as described.

2. In a tabulating attachment for type-writing machines, the combination, with the transversely movable paper-carriage, of a rock shaft, a plurality of stops mounted upon said shaft and independently adjustable longitudinally thereof, and adapted to coöperate successively with the paper-carriage to 20 arrest it in different columnar positions determined by such adjustment of the stops, and a plurality of tabulator keys and connections for turning said rock shaft to adjust said stops to arrest the paper-carriage at the 25 desired denominational positions in the different columns; substantially as described.

3. In a tabulating attachment for type-writing machines, the combination, with the transversely movable paper carriage provided with a graduated contact piece, of a rock shaft, a stop mounted thereon and adapted to coöperate with the graduated contact piece on the paper carriage, and a plurality of tabulator keys and connections for 40 turning the rock shaft to adjust the stop relatively to the graduations of said contact piece; substantially as described.

4. In a tabulating attachment for type-writing machines, the combination, with the transversely movable paper carriage, provided with a graduated contact piece, of a rock shaft, a stop mounted upon said shaft and adjustable longitudinally thereof and adapted to coöperate with the graduated 50 contact piece on the paper-carriage, and a plurality of tabulator keys and connections for turning said rock shaft to adjust said stop relatively to the graduations of said contact piece; substantially as described.

60 5. In a tabulating attachment for type-writing machines, the combination, with the transversely movable paper-carriage provided with a graduated contact piece, of a rock shaft, a plurality of stops mounted upon 65 said shaft and adapted to coöperate success-

sively with the graduated contact piece on the paper-carriage, and a plurality of tabulator keys and connections for turning the rock shaft to adjust the said stops relatively to the graduations of said contact piece; substantially as described. 70

6. In a tabulating attachment for type-writing machines, the combination, with the transversely movable paper-carriage provided with a graduated contact piece, of a rock shaft, a plurality of stops mounted upon said shaft and independently adjustable longitudinally thereof, and adapted to coöperate successively with the graduated contact piece upon the paper-carriage, and a plurality of tabulator keys and connections for turning the rock shaft to simultaneously adjust said stops relatively to the graduations of the contact piece; substantially as described. 75 80

7. In a tabulating attachment for type-writing machines, the combination, with the transversely movable paper-carriage, of a stop for arresting the paper-carriage in different denominational positions and also adjustable transversely of the machine to different columnar positions, and a plurality of tabulator keys and connections for adjusting said stop to arrest the paper-carriage in desired denominational position; substantially 90 95 as described.

8. In a tabulating attachment for type-writing machines, the combination, with the transversely movable paper-carriage, of a plurality of stops for successively arresting the paper-carriage at different columnar positions, and a plurality of tabulator keys and connections for adjusting said stops simultaneously to position to arrest the paper-carriage at any desired denominational position in the column; substantially as described. 100 105

9. In a tabulating attachment for type-writing machines, the combination, with the transversely movable paper-carriage, of a plurality of stops for successively arresting said carriage at different columnar positions, said stops being also independently adjustable transversely of the machine to vary the positions of the columns as desired, and a plurality of tabulator keys and connections for adjusting said stops simultaneously to arrest the paper-carriage at any desired denominational position in the column; substantially as described. 110 115 120

10. In a tabulating attachment for type-writing machines, the combination, with the transversely movable paper-carriage, of an adjustable stop for arresting the paper-carriage in different denominational positions, and a plurality of tabulator keys and connections for adjusting said stop and releasing the paper-carriage by the operation of any one of said keys; substantially as described. 125 130

11. In a tabulating attachment for type-writing machines, the combination, with the transversely movable paper-carriage, of a stop movable transversely of the machine 5 by hand and adapted to be set in different columnar positions, and also adjustable to arrest the paper-carriage in different denominational positions in the column, and a plurality of tabulator keys and connections for 10 adjusting the stop and releasing the paper-carriage by the operation of any one of said keys; substantially as described.
12. In a tabulating attachment for type-writing machines, the combination, with the 15 transversely movable paper-carriage, of a plurality of stops for successively arresting the paper-carriage at different columnar positions, and a plurality of tabulator keys and connections for adjusting said stops simultaneously to arrest the paper-carriage at any 20 desired denominational position in the column and releasing the paper-carriage by the operation of any one of said keys; substantially as described.
13. In a tabulating attachment for type-writing machines, the combination, with the transversely movable paper-carriage, of a 25 plurality of stops for successively arresting the paper-carriage at different columnar positions, said stops being independently movable transversely of the machine and adapted to be set by hand to different columnar positions, and a plurality of tabulator keys and connections for adjusting said stops simultaneously to arrest the paper-carriage in any 30 desired denominational position in the column and releasing the paper-carriage by the operation of any one of said keys; substantially as described.
14. In a tabulating attachment for type-writing machines, the combination, with the transversely movable paper-carriage, provided with a graduated contact piece, of a 35 stop adapted to coöperate with said contact piece to arrest the paper-carriage at different denominational positions, and a plurality of tabulator keys and connections for adjusting said stop relatively to the graduations of the contact piece and releasing the 40 paper-carriage by the operation of any one of said keys; substantially as described.
15. In a tabulating attachment for type-writing machines, the combination, with the transversely movable paper-carriage, provided with a graduated contact piece, of a 45 stop adjustable transversely of the machine to different columnar positions also adjustable relatively to the graduations of the contact piece, and a plurality of tabulator keys and connections for adjusting said stop relatively to the graduations of the contact piece to arrest the paper-carriage in desired 50 denominational positions; substantially as described.
16. In a tabulating attachment for type-writing machines, the combination, with the transversely movable paper-carriage provided with a graduated contact piece, of a plurality of stops adapted to coöperate successively with the contact piece upon the paper-carriage to arrest the latter in different columnar positions, and a plurality of tabulator keys and connections for adjusting said stops simultaneously relatively to the graduations of the contact piece, to arrest the paper-carriage at the desired denominational position in any column; substantially as described.
17. In a tabulating attachment for type-writing machines, the combination, with the transversely movable paper-carriage, provided with a graduated contact piece, of a stop adjustable transversely of the machine to different columnar positions, and also adjustable relatively to the graduations of the contact piece, and a plurality of tabulator keys and connections between the same and said stop and the escapement mechanism of the machine for adjusting said stop relatively to the graduations of the contact piece and releasing the paper-carriage by the operation of any one of said keys; substantially as described.
18. In a tabulating attachment for type-writing machines, the combination, with the transversely movable paper-carriage provided with a graduated contact piece, of a plurality of stops adapted to coöperate successively with the contact piece upon the paper-carriage to arrest the latter in different columnar positions, and a plurality of tabulator keys and connections between the same and said stop and the escapement mechanism of the machine for adjusting said stops simultaneously relatively to the graduations of the contact piece and releasing the paper-carriage by operation of any one of said keys; substantially as described.
19. In a tabulating attachment for type-writing machines, the combination, with the transversely movable paper-carriage, of a rock-shaft, a stop mounted upon said shaft and adapted to coöperate with the paper-carriage to arrest the latter at different denominational positions, and a plurality of tabulator keys for turning the said rock-shaft to adjust said stop and releasing the paper-carriage by the operation of any one of said keys; substantially as described.
20. In a tabulating attachment for type-writing machines, the combination, with the transversely movable paper-carriage, of a rock shaft, a stop mounted thereon and adjustable longitudinally thereof to different columnar positions, and also adjustable to arrest the paper-carriage at different denominational positions, and a plurality of tabulator keys and connections for turning said

rock shaft to adjust the stop and releasing the paper-carriage by the operation of any one of said keys, substantially as described.

21. In a tabulating attachment for type-writing machines, the combination, with the transversely movable paper-carriage, of a rock shaft, a plurality of stops mounted thereon and adapted to coöperate successively with the paper-carriage to arrest the latter in different columnar positions, and a plurality of tabulator keys and connections between the same and the rock shaft and the escapement mechanism of the machine for turning said shaft to adjust the stops and releasing the paper-carriage by the operation of any one of said keys; substantially as described.

22. In a tabulating attachment for type-writing machines, the combination, with the transversely movable paper-carriage provided with a graduated contact piece, of a rock shaft, a stop mounted upon said rock-shaft and adapted to coöperate with the graduated contact piece upon the paper-carriage, and a plurality of tabulator keys and connections between the same and the rock shaft and the escapement mechanism of the machine for turning the rockshaft to adjust the stop relatively to the graduations of said contact piece and releasing the paper-carriage by the operation of any one of said keys; substantially as described.

23. In a tabulating attachment for type-writing machines, the combination, with the transversely movable paper-carriage provided with a graduated contact piece, of a rockshaft, a stop mounted upon said shaft and adjustable longitudinally thereof, of a plurality of tabulator keys and connections between the same and the rock shaft and the escapement mechanism of the machine for turning said rock shaft to adjust said stop relatively to the graduations of said contact piece and releasing the paper-carriage by the operation of any one of said keys; substantially as described.

24. In a tabulating attachment for type-writing machines, the combination, with the transversely movable paper-carriage provided with a graduated contact piece, of a rock shaft, and a plurality of stops mounted upon said shaft and adapted to coöperate successively with the graduated contact piece on the paper-carriage, and a plurality of tabulator keys and connections between the same and the rock shaft and the escapement mechanism of the machine for turning the rock shaft to adjust said stops relatively to the graduations of said contact piece and releasing the paper-carriage by the operation of any one of said keys; substantially as described.

25. In a tabulating attachment for type-writing machines, the combination, with the transversely movable paper carriage, of a stop, means for adjusting said stop to arrest

the paper carriage in different denominational positions, and means for automatically throwing said stop into an abnormal position out of coöperative relation with the paper carriage, after the latter has been arrested in a given denominational position by said stop; substantially as described.

26. In a tabulating attachment for type-writing machines, the combination, with the transversely movable paper carriage, of a stop; means for adjusting said stop to arrest the paper carriage in different denominational positions, means for automatically throwing said stop out of coöperative relation with the paper carriage after the latter has been arrested in a given denominational position by the stop, and means operated by the return movement of the paper carriage to restore the stop to its normal relation with the paper carriage; substantially as described.

27. In a tabulating attachment for type-writing machines, the combination, with the transversely movable paper carriage, of a plurality of stops for arresting the paper carriage at different columnar positions, means for adjusting said stops to arrest the paper carriage at different denominational positions in the several columns, and means operating upon each stop independently of the other stops for automatically throwing each stop out of coöperative relation with the paper carriage after the latter has been arrested by such stop, to permit free movement of the carriage to the next succeeding stop; substantially as described.

28. In a tabulating attachment for type-writing machines, the combination, with the transversely movable paper carriage, of a plurality of stops for arresting the paper carriage at different columnar positions, means for adjusting said stops to arrest the paper carriage at different denominational positions in the several columns, means for automatically throwing each stop out of coöperative relation with the paper carriage after the latter has been arrested by such stop, to permit free movement of the carriage to the next succeeding stop, and means operated by the return-movement of the paper carriage to restore all of the stops to normal relation with the paper carriage; substantially as described.

29. In a tabulating attachment for type-writing machines, the combination, with the transversely movable paper carriage provided with a graduated contact piece, of a stop adapted to coöperate with said contact piece to arrest the paper carriage at different denominational positions, means for adjusting said stop relatively to the graduations of said contact piece, and means for automatically moving said stop into an abnormal position, out of the path of travel of said contact piece, after the paper carriage has been arrested by it; substantially as described.

30. In a tabulating attachment for type-writing machines, the combination, with the transversely movable paper carriage provided with a graduated contact piece, of a 5 stop adapted to coöperate with said contact piece to arrest the paper carriage at different denominational positions, means for adjusting said stop relatively to the graduations of said contact piece, means for automatically 10 moving said stop out of the path of travel of said contact piece after the paper carriage has been arrested by it, and means operated by the return movement of the paper carriage to restore the stop to normal position; 15 substantially as described.

31. In a tabulating attachment for type-writing machines, the combination, with the transversely movable paper carriage provided with a graduated contact piece, of a 20 plurality of stops adapted to coöperate successively with said contact piece, to arrest the paper carriage at different columnar positions, means for adjusting said stops simultaneously relatively to the graduations of 25 said contact piece, and means operating on each stop independently of the other stops for automatically moving the stop out of the path of said contact piece after the paper carriage has been arrested by it, to permit free 30 movement of the carriage to the next succeeding stop; substantially as described.

32. In a tabulating attachment for type-writing machines, the combination, with the transversely movable paper carriage provided with a graduated contact piece of a 35 plurality of stops adapted to coöperate successively with said contact piece, to arrest the paper carriage at different columnar positions, means for adjusting said stops simultaneously relatively to the graduations of 40 said contact piece, means for automatically moving each stop out of the path of said contact piece after the paper carriage has been arrested by it, to permit free movement of 45 the carriage to the next succeeding stop, and means operated by the return movement of the paper carriage to restore the stops to normal position; substantially as described.

33. In a tabulating attachment for type-writing machines, the combination, with the transversely movable paper carriage, of a 50 stop, a plurality of tabulator keys and connections for adjusting said stop to arrest the paper carriage in different denominational positions, and means for automatically 55 throwing said stop out of coöoperative relation with the paper carriage after the latter has been arrested by the stop in a given denominational position and prior to the operation of a type key; substantially as described.

34. In a tabulating attachment for type-writing machines, the combination, with the transversely movable paper carriage, of a 60 stop, a plurality of tabulator keys and con-

nections for adjusting said stop to arrest the paper carriage in different denominational positions, means for automatically throwing said stop out of coöoperative relation with the paper carriage after the latter has been arrested by the stop in a given denominational position, and means operated by the return movement of the paper carriage to restore the stop to its normal relation with the paper carriage; substantially as described. 75

35. In a tabulator attachment for type-writing machines, the combination, with the transversely movable paper carriage, of a plurality of column stops for arresting it at different columnar positions, a plurality of 80 tabulator keys and connections for adjusting the stops to arrest the paper carriage at different denominational positions in the several columns, and means for automatically throwing each stop out of coöoperative relation to the paper carriage after the latter has been arrested by such stop, to permit free movement of the carriage to the next succeeding stop; substantially as described. 85

36. In a tabulator attachment for type-writing machines, the combination, with the transversely movable paper carriage, of a plurality of stops for arresting it at different columnar positions, a plurality of tabulator keys and connections for adjusting the stops 95 to arrest the paper carriage at different denominational positions in the several columns, means for automatically throwing each stop out of coöoperative relation to the paper carriage after the latter has been arrested by such stop, to permit free movement of the carriage to the next succeeding stop, and means operated by the return movement of the paper carriage to restore the stops to normal relation to the paper 100 carriage; substantially as described. 105

37. In a tabulating attachment for type-writing machines, the combination, with the transversely movable paper carriage provided with a graduated contact piece, of a 110 stop adapted to coöperate with said contact piece to arrest the paper carriage at different denominational positions, a plurality of tabulator keys and connections for adjusting the stop relatively to the graduations of the contact piece, and means for automatically moving said stop out of normal operative position after the paper carriage has been arrested by the stop; substantially as described. 115

38. In a tabulating attachment for type-writing machines, the combination, with the transversely movable paper carriage provided with a graduated contact piece, of a 120 stop adapted to coöperate with said contact piece to arrest the paper carriage at different denominational positions, a plurality of tabulator keys and connections for adjusting the stop relatively to the graduations of the contact piece, means for automatically moving 130

said stop out of the path of said contact piece after the paper carriage has been arrested by the stop, and means operated by the return movement of the paper carriage 5 to restore the stop to normal position; substantially as described.

39. In a tabulating attachment for type-writing machines, the combination, with the transversely movable paper carriage provided with a graduated contact piece, of a plurality of stops adapted to successively cooperate with said contact piece to arrest the paper carriage in different columnar positions, a plurality of tabulator keys and connections for adjusting said stops relatively to the graduations of said contact piece, and means for automatically moving each stop out of the path of said contact piece after the paper carriage has been arrested by such stop, to permit free movement of the carriage to the next succeeding stop; substantially as described.

40. In a tabulating attachment for type-writing machines, the combination, with the transversely movable paper carriage provided with a graduated contact piece, of a plurality of stops adapted to successively cooperate with said contact piece to arrest the paper carriage in different columnar positions, a plurality of tabulator keys and connections for adjusting said stops relatively to the graduations of said contact piece, means for automatically moving each stop out of the path of said contact piece after the paper carriage has been arrested by such stop, to permit free movement of the carriage to the next succeeding stop, and means operated by the return movement of the paper carriage to restore the stops to normal position; substantially as described.

41. In a tabulating attachment for type-writing machines, the combination, with the transversely movable paper carriage, of a stop for arresting the paper carriage at different denominational positions, a plurality of tabulator keys and connections between the same and said stop and the escapement mechanism of the machine for adjusting said stop and releasing the paper carriage by the operation of any one of said keys, and means for automatically throwing said stop out of coöperative relation with the paper carriage after the latter has been arrested by said stop; substantially as described.

42. In a tabulating attachment for type-writing machines, the combination, with the transversely movable paper carriage, of a stop for arresting the paper carriage at different denominational positions, a plurality 60 of tabulator keys and connections between the same and said stop and the escapement mechanism of the machine for adjusting said stop and releasing the paper carriage by the operation of any one of said keys, means for 65 automatically throwing said stop out of co-

operative relation with the paper carriage after the latter has been arrested by said stop, and means operated by the return movement of the paper carriage to restore the stop to its normal relation to the paper carriage; substantially as described.

43. In a tabulating attachment for type-writing machines, the combination, with the transversely movable paper carriage, of a plurality of stops for arresting the paper carriage at different columnar positions, a plurality of tabulator keys and connections between the same and the stops and the escapement mechanism of the machine for releasing the paper carriage and adjusting said stops to arrest the paper carriage at different denominational positions in the several columns, and means for automatically throwing each stop out of coöperative relation with the paper carriage after the latter has been arrested by such stop, to permit free movement of the carriage to the next succeeding stop; substantially as described.

44. In a tabulating attachment for type-writing machines, the combination, with the transversely movable paper carriage, of a plurality of stops for arresting the paper carriage at different columnar positions, a plurality of tabulator keys and connections between the same and the stops and the escapement mechanism of the machine for releasing the paper carriage and adjusting said stops to arrest the paper carriage at different denominational positions in the several columns, means for automatically throwing each stop out of coöperative relation with the paper carriage after the latter has been arrested by such stop, to permit free movement of the carriage to the next succeeding stop, and means operated by the return movement of the paper carriage to restore the stops to normal relation to the paper carriage; substantially as described.

45. In a tabulating attachment for type-writing machines, the combination, with the transversely movable paper carriage provided with a graduated contact piece, of a stop adapted to coöperate with said contact piece to arrest the paper carriage at different denominational positions, a plurality of tabulator keys and connections between the same and said stop and the escapement mechanism of the machine for adjusting said stop relatively to the graduations of said contact piece and releasing the paper carriage, and means for automatically moving said stop out of the path of said contact piece after the paper carriage has been arrested by said stop; substantially as described.

46. In a tabulating attachment for type-writing machines, the combination, with the transversely movable paper carriage provided with a graduated contact piece, of a stop adapted to coöperate with said contact piece to arrest the paper carriage at different

denominational positions, a plurality of tabulator keys and connections between the same and said stop and the escapement mechanism of the machine for adjusting said stop relatively to the graduations of said contact piece and releasing the paper carriage, means for automatically moving said stop out of the path of said contact piece after the paper carriage has been arrested by said stop, and means operated by the return movement of the paper carriage to restore the stop to normal position; substantially as described.

47. In a tabulating attachment for type-writing machines, the combination, with the transversely movable paper carriage provided with a graduated contact piece, of a plurality of stops adapted to coöperate successively with said contact piece to arrest the paper carriage at different columnar positions, a plurality of tabulator keys and connections between the same and the stops and the escapement mechanism of the machine for releasing the paper carriage and adjusting said stops relatively to the graduations of the contact piece, and means for automatically moving each stop out of the path of the contact piece after the paper carriage has been arrested by said stop, to permit free movement of the paper carriage to the next succeeding stop; substantially as described.

48. In a tabulating attachment for type-writing machines, the combination, with the transversely movable paper carriage provided with a graduated contact piece, of a plurality of stops adapted to coöperate successively with said contact piece to arrest the paper carriage at different columnar positions, a plurality of tabulator keys and connections between the same and the stops and the escapement mechanism of the machine for releasing the paper carriage and adjusting said stops relatively to the graduations of the contact piece, means for automatically moving each stop out of the path of the contact piece after the paper carriage has been arrested by said stop, to permit free movement of the paper carriage to the next succeeding stop, and means operated by the return movement of the paper carriage to restore the stops to normal position; substantially as described.

49. In a tabulating attachment for type-writing machines, the combination, with the transversely movable paper carriage, of a rock shaft, a plurality of stops mounted upon said shaft for arresting the paper carriage at different columnar positions, means for turning said rock-shaft to adjust said stops to arrest the paper carriage in different denominational positions in the several columns, and means for automatically throwing each stop into an abnormal position, out of coöoperative relation with the paper carriage, after the latter has been arrested by such stop, to permit free movement of the carriage to the

next succeeding stop; substantially as described.

50. In a tabulating attachment for type-writing machines, the combination, with the transversely movable paper carriage, of a rock-shaft, a plurality of stops mounted upon said shaft for arresting the paper carriage at different columnar positions, means for turning said rock-shaft to adjust said stops to arrest the paper carriage in different denominational positions in the several columns, means for automatically throwing each stop out of coöoperative relation with the paper carriage after the latter has been arrested by such stop, to permit free movement of the carriage to the next succeeding stop, and means operated by the return movement of the paper carriage to restore all of the stops to normal relation to the paper carriage; substantially as described.

51. In a tabulating attachment for type-writing machines, the combination, with the transversely movable paper carriage provided with a graduated contact piece, of a rock-shaft, a plurality of stops mounted thereon and adapted to coöperate successively with said contact piece, to arrest the paper carriage at different columnar positions, means for turning the rock-shaft to adjust said stops relatively to the graduations of said contact piece, and means operating on each stop independently of the other stops, for automatically moving the stop out of the path of said contact piece after the paper carriage has been arrested by such stop, to permit free movement of the carriage to the next succeeding stop; substantially as described.

52. In a tabulating attachment for type-writing machines, the combination, with the transversely movable paper carriage provided with a graduated contact piece, of a rock-shaft, a plurality of stops mounted thereon and adapted to coöperate successively with said contact piece, to arrest the paper carriage at different columnar positions, means for turning the rock-shaft to adjust said stops relatively to the graduations of said contact piece, means for automatically moving each stop out of the path of said contact piece after the paper carriage has been arrested by such stop, to permit free movement of the carriage to the next succeeding stop, and means operated by the return movement of the paper carriage to restore the stops to normal position; substantially as described.

53. In a tabulating attachment for type-writing machines, the combination, with the transversely movable paper carriage, of a rock-shaft, a plurality of stops mounted upon said shaft for arresting the paper carriage at different columnar positions, a plurality of tabulator keys and connections for turning said rock shaft to adjust said stops

to arrest the paper carriage in different denominational positions in the several columns, and means for automatically throwing each stop out of coöperative relation with the paper carriage after the latter has been arrested by such stop, to permit free movement of the carriage to the next succeeding stop; substantially as described.

54. In a tabulating attachment for type-writing machines, the combination, with the transversely movable paper carriage, of a rock-shaft, a plurality of stops mounted upon said shaft for arresting the paper carriage at different columnar positions, a plurality of tabulator keys and connections for turning said rock-shaft to adjust said stops to arrest the paper carriage in different denominational positions in the several columns, means for automatically throwing each stop out of coöperative relation with the paper carriage after the latter has been arrested by such stop, to permit free movement of the carriage to the next succeeding stop, and means operated by the return movement of the paper carriage to restore all of the stops to normal relation to the paper carriage; substantially as described.

55. In a tabulating attachment for type-writing machines, the combination, with the transversely movable paper carriage provided with a graduated contact piece, of a rock-shaft, a plurality of stops mounted thereon and adapted to coöperate successively with said contact piece to arrest the paper carriage at different columnar positions, a plurality of tabulator keys and connections for turning the rock-shaft to adjust said stops relatively to the graduations of said contact piece, and means for automatically moving each stop out of the path of said contact piece after the paper carriage has been arrested by such stop, to permit free movement of the carriage to the next succeeding stop; substantially as described.

56. In a tabulating attachment for type-writing machines, the combination, with the transversely movable paper carriage provided with a graduated contact piece, of a rock-shaft, a plurality of stops mounted thereon and adapted to coöperate successively with said contact piece, to arrest the paper carriage at different columnar positions, a plurality of tabulator keys for turning the rock-shaft to adjust the stops relatively to the graduations of said contact piece, means for automatically moving each stop out of the path of said contact piece after the paper carriage has been arrested by such stop, to permit free movement of the carriage to the next succeeding stop, and means operated by the return movement of the paper carriage to restore the stops to normal position; substantially as described.

57. In a tabulating attachment for type-writing machines, the combination, with the

transversely movable paper carriage, of a rock - shaft, a plurality of stops mounted thereon and coöoperating with the paper carriage to arrest the latter at different columnar positions, a plurality of tabulator keys and connections between the same and the rock shaft and the escapement mechanism of the machine for releasing the paper carriage and turning the rock-shaft to adjust the stops to arrest the paper carriage at different denominational positions in the several columns, and means for automatically throwing each stop out of coöperative relation with the paper carriage after the latter has been arrested by such stop, to permit free movement of the carriage to the next succeeding stop; substantially as described.

58. In a tabulating attachment for type-writing machines, the combination, with the transversely movable paper carriage, of a rock - shaft, a plurality of stops mounted thereon and coöoperating with the paper carriage to arrest the latter at different columnar positions, a plurality of tabulator keys and connections between the same and the rock shaft and the escapement mechanism of the machine for releasing the paper carriage and turning the rock-shaft to adjust the stops to arrest the paper carriage at different denominational positions in the several columns, means for automatically throwing each stop out of coöperative relation with the paper carriage after the latter has been arrested by such stop, to permit free movement of the carriage to the next succeeding stop, and means operated by the return movement of the paper carriage to restore the stops to normal relation to the paper carriage; substantially as described.

59. In a tabulating attachment for type-writing machines, the combination, with the transversely movable paper carriage provided with a graduated contact piece, of a rock - shaft, a plurality of stops mounted thereon and adapted to coöperate successively with such contact piece to arrest the paper carriage at different columnar positions, a plurality of tabulator keys and connections between the same and the rock shaft and the escapement mechanism of the machine for releasing the paper carriage and turning the rock-shaft to adjust said stops relatively to the graduations of the contact piece, and means for automatically moving each stop out of the path of the contact piece after the paper carriage has been arrested by such stop, to permit free movement of the paper carriage to the next succeeding stop; substantially as described.

60. In a tabulating attachment for type-writing machines, the combination, with the transversely movable paper carriage provided with a graduated contact piece, of a rock - shaft, a plurality of stops mounted thereon and adapted to coöperate suc-

sively with such contact piece, to arrest the paper carriage at different columnar positions, a plurality of tabulator keys and connections between the same and the rock shaft 5 and the escapement mechanism of the machine for releasing the paper carriage and turning the rock shaft to adjust said stops relatively to the graduations of the contact piece, means for automatically moving each 10 stop out of the path of the contact piece after the paper carriage has been arrested by such stop, to permit free movement of the paper carriage to the next succeeding stop, and means operated by the return movement of 15 the paper carriage to restore the stops to normal position; substantially as described.

61. The combination, with the paper carriage provided with a graduated contact piece I', of the rock-shaft K', the disk or support B' mounted thereon and turning therewith, the stop plate C' pivoted upon said disk and provided with the stop projection J' co-operating with the contact piece I', and means for holding the stop plate C' in its opposite positions upon the disk B'; substantially as described.

62. The combination, with the paper carriage provided with a graduated contact piece I', of the rock-shaft K', the disk or support B' mounted thereon and turning therewith, the stop plate C' pivoted upon said disk and provided with the stop projection J' co-operating with the contact piece I', and the spring plunger h' interposed between the disk 30 B' and plate C' and co-operating with the recesses j', k' to hold the plate C' in its opposite positions; substantially as described.

63. The combination, with the paper carriage provided with a graduated contact piece I', of the rock-shaft K', the disk or support B' mounted thereon and turning therewith, the stop plate C' pivoted upon the disk B' and provided with the stop projection J' co-operating with the contact piece I', the 45 spring g' between the disk and plate, and means for holding the plate in its opposite positions upon the disk; substantially as described.

64. The combination, with the paper carriage provided with a graduated contact piece, of the rock-shaft K', the disk or support B' mounted thereon and turning therewith, the stop plate C' pivoted upon said disk and provided with the stop projection J' and resetting projection e', means upon 50 the paper carriage co-operating with said projection e' to return the plate C' to normal position upon the disk B' at the return movement of the paper carriage, and means for holding the plate C' in its opposite position upon said disk; substantially as described.

65. The combination, with the paper carriage provided with a graduated contact piece I' and wiper arm D', of the rock shaft

K', the disk or support B' mounted thereon and turning therewith, the stop plate C' pivoted upon the disk B' and provided with the stop projection J' and the resetting projection e', the former co-operating with the contact piece I' and the latter with the wiper arm D', and means for holding the plate C' in its opposite positions upon the disk B'; substantially as described.

66. The combination, with the rock-shaft K' mounted in the fixed frame of the machine and carrying stop projections, of the paper carriage provided with a graduated contact piece I' curved concentrically to the rock-shaft and adapted to co-operate successively with the stops thereon, and means for 75 turning the rock shaft and releasing the paper carriage; substantially as described.

67. The combination, with the shaft K' provided with the longitudinal groove a' and the rack b', of the sleeve A' provided with 85 the projection c' co-operating with the groove and rack of the shaft; substantially as described.

68. The combination, with the shaft K' provided with a longitudinal groove a' and 90 rack b', of the sleeve A' provided with a projection c' co-operating with said groove and rack, and a spring d' operating to yieldingly hold the projection c' in engagement with the rack; substantially as described.

69. The combination, with the shaft K' provided with the longitudinal groove a' and rack b', of the sleeve A' mounted to turn and slide upon said shaft, and provided at one end with the milled thumb-piece a'', and at 100 its opposite end with the disk B' carrying a stop projection J', a projection c' on said sleeve adapted to co-operate with the groove a' and rack b', and the spring d' interposed between the sleeve and shaft and operating 105 to yieldingly hold the projection c' in engagement with the rack b'; substantially as described.

70. In a typewriting machine and tabulating mechanism, the combination of a carriage, denominational stops carried by the carriage, a revoluble tabulating stop carried by a fixed portion of the machine and movable in a plane fore and aft of the machine, and key-actuated means for turning the tabulating stop to different extents and into the paths of the different denominational stops.

71. In a typewriting machine and tabulating mechanism, the combination of a carriage, a series of segmentally arranged denomination stops carried by the carriage, a tabulating stop carried by the frame of the machine and adapted to co-operate with the denomination stops and a frost the carriage, and means for turning said tabulating stop 120 and into operative relation to the denomination stops.

72. In a typewriting machine and tabu-

lating mechanism, the combination of a carriage, a series of segmentally arranged denomination stops which are carried by the carriage, a rock shaft which extends in the direction of the travel of the carriage and which turns in bearings on the frame of the machine, a tabulating stop secured to turn with said rock shaft, and key-actuated means for turning the shaft to different extents to project the tabulating stop thereon into the path of the different denomination stops on the carriage.

73. In a typewriting machine and tabulating mechanism, the combination of a carriage, a series of segmentally arranged denomination stops which are carried by the carriage, a rock shaft which extends in the direction of the travel of the carriage and which turns in bearings on the frame of the machine, a tabulating stop secured to turn with said rock shaft, key-actuated means for turning the shaft to different extents to bring the tabulating stop thereon into the path of the different denomination stops on the carriage, and means controlled by said key actuated means for releasing the carriage.

74. In a typewriting machine and tabulating mechanism, the combination of a carriage, a series of segmentally arranged denomination stops which are fixed relatively to the part that carries them, a rock shaft which extends in the direction of the travel of the carriage, a tabulating stop which is adjustable on, but is secured to turn with said rock shaft, and key actuated means for turning the shaft.

75. In a typewriting machine and tabulating mechanism, the combination of a carriage, a plurality of denominational stops fixedly arranged with reference to the part which carries them and spirally arranged in different vertical planes transversely of the carriage, a rock shaft, a tabulating stop carried by said rock shaft, a plurality of keys, each of which is adapted to turn said rock shaft to a different extent so as to bring the stop thereon into coöperation with different denominational stops to arrest the carriage in different denominational positions.

76. In a typewriting machine and in tabulating mechanism, the combination of a carriage, a plurality of denominational stops rigidly secured to the carriage and segmentally arranged and situated at letter space distances apart, a rock shaft carried by the frame of the machine, a tabulating stop carried by said rock shaft and adjustable therein, and adapted to coöperate with any of the denominational stops on the carriage, a plurality of keys, each of which is adapted to turn the rock shaft to a different extent to bring the stop thereon into the paths of the different denominational stops on the carriage and means controlled by said keys for

effecting the release of the carriage upon the actuation of any of said keys.

77. In a typewriting machine and tabulating mechanism, the combination of a carriage, a tabulating stop, segmentally and spirally arranged denominational stops which are spaced apart to permit the tabulating and denominational stops to pass one another in a transverse direction, there being a space between the terminal denominational stops to permit a free longitudinal movement of the denominational and tabulating stops past one another during the travel of the carriage when the tabulating mechanism is not in operation, and means for interposing one of said tabulating and denominational stops in the path of the other.

78. In a typewriting machine and tabulating mechanism, the combination of a carriage, a tabulating stop on the frame of the machine, a series of denomination stops on the carriage, a plurality of tabulating key levers, a universal frame, means connected to said frame to move said tabulating stop, and means for variably moving the universal frame by said key levers, whereby the tabulating stop is variably moved.

79. In a typewriting machine and tabulating mechanism, the combination of a carriage, a tabulating stop on the frame of the machine, a series of denomination stops on the carriage, a universal frame, means connected to said frame to move said tabulating stop, a series of key levers and means for enabling them to act on said frame variably to variably operate said tabulating stop, a second universal frame which receives motion from said key levers, and means controlled by said second universal frame for releasing the carriage.

80. In a typewriting machine and tabulating mechanism, the combination of a power driven carriage, a tabulating stop on the frame of the machine, a series of denomination stops on the carriage, a universal frame connected to said tabulating stop, and a series of key levers operatively connected to said universal frame so as to move it different distances.

81. In a typewriting machine and tabulating mechanism, the combination of a carriage, a tabulating stop, coöperating denominational stops, a universal frame, means connected to said frame to move said tabulating stop to different extents, and tabulating key levers which exert leverage on the universal frame, the leverage action of the different key levers on said frame being different to move the frame to different extents.

82. In a typewriting machine and tabulating mechanism, the combination of a carriage, a series of denomination stops, a tabulating stop movable to a plurality of denominational positions, a universal bar connected

to said stop, and a plurality of denominational key levers all acting on said universal bar to variably move the tabulating stop.

83. In a typewriting machine and tabulating mechanism, the combination of a carriage, a series of denomination stops, a tabulating stop movable to a plurality of denominational positions, a universal bar connected to said tabulating stop, and a plurality of denominational key levers all acting on said universal bar to variably move the tabulating stop, the key levers having a common pivot and provided with contacts at different distances from said pivot to variably move the universal bar and stops.

84. In a typewriting machine and tabulating mechanism, the combination of a carriage, escapement mechanism, denomination stops, a tabulating stop, a series of denominational key levers having projections or lips of different lengths, a universal frame operable by said key levers, and connections from the said frame to the escapement mechanism to separate same and release the carriage.

85. In a typewriting machine and tabulating mechanism, the combination of a series of stepped denominational stops, a single stop adapted to be moved different degrees to cooperate with said series of stepped stops, a universal bar connected with said variably movable stop, a series of key-actuated bars provided each with means for moving said universal bar, said means on said key-actuated bars being graded to move the said uni-

versal bar and the said stop connected there- 35 to varying degrees.

86. In a typewriting machine and tabulating mechanism, the combination of a carriage, denominational stops carried by the carriage, a coöperating tabulating stop 40 which is adapted to move to different extents and into the path of the different denominational stops on the carriage, an actuator operatively connected to said tabulating stop, a series of tabulating or denominational keys 45 which are independently mounted in the frame of the machine and coöperate with said actuator to move the tabulating stop to different extents, and means for releasing the carriage. 50

87. In a key-operated machine, a carriage, a tabulating stop which according to the extent of its movement from its normal position will arrest the carriage at different points, a tabulating bar operatively connected with said stop, a release bar adjacent to said tabulating bar, a carriage-release mechanism connected with said release bar, and a plurality of keys each having a toe arranged to engage the tabulating bar, and another toe 55 arranged for engagement with the release bar, the toes which operate the tabulating bar being of different length for each key. 60
